UNITED STATES PATENT OFFICE

2,522,388

DETACHABLE HANDLE SCREW DRIVER

Gunnar Madsen, Brooklyn, N. Y.

Application March 26, 1949, Serial No. 83,737

1 Claim. (Cl. 279—104)

1

This invention relates to a detachable handle screw driver and the like.

It is an object of the present invention to provide a detachable handle for screw drivers and the like wherein the screw driver shanks can be replaced by one another and wherein there is a simple detachable connection for the shank and the screw driver handle and wherein if the wood part of the handle cracks or breaks it can be readily replaced with another wood handle part.

Other objects of the present invention are to provide a detachable handle screw driver which is of simple construction, inexpensive to manufacture, consumes little space in storage, economical to use and efficient in operation.

For other objects and for a better understanding of the present invention, reference may be had to the following detailed description taken in connection with the accompanying drawing, in which

Fig. 1 is a collective and perspective view of the screw driver embodying the features of the present invention and with certain of the shanks lying free of the handle.

Fig. 2 is an enlarged longitudinal sectional view taken through the handle and on line 2—2 of Fig. 1.

Fig. 3 is a transverse sectional view taken on line 3—3 of Fig. 2.

Referring now to the figures, 10 represents the main part of a handle. This part is made preferably of light strong metal and is provided with a central squared bore 11 to receive a squared attaching portion 12 of a screw driver shank 13 having a screw-engaging portion 14 on its outer end. This shank has an enlargement 15 from which the attaching portion 12 extends. A ball detent 16 is provided in the attaching portion 12 and will enter an opening 17 in the main handle part 10 to prevent the axial displacement of the shank from the part 10. Connected to the main part 10 and extending upwardly therefrom is a rod portion 18 having a threaded opening 19 in its upper end and two vanes diametrically opposed to one another at its lower end as indicated at 20. A wood or plastic handle part 21 is carried upon the rod projection 18. To keep it from turning relative thereto, it is provided with slots for receiving the vanes 20.

The wood or plastic handle part 21 is held upon the rod against axial displacement there-

from by a plate 22 extending over the end of the part 21 and a bolt 23 having a rounded head 24 forming the end of the screw driver handle is threaded into the threaded opening of the rod 18. Should the wood or plastic part 21 become broken, it is an easy matter to remove the bolt 24 and the plate 22 to replace the part 21.

It will be understood that the screw driver shanks can be of any shape as long as they have the same type of attaching portion and may conform to shapes 25 and 26 lying free of the handle and as shown in Fig. 1.

While various changes may be made in the detail construction, it shall be understood that such changes shall be within the spirit and scope of the present invention as defined by the appended claim.

Having thus set forth and disclosed the nature of my invention, what is claimed is:

A screw driver or the like device comprising a main handle part having a central squared opening, a screw driver shank having an attaching portion adapted to fit the squared opening of the handle part in a removable manner, a rod portion extending upwardly from the handle part, a threaded opening, a vane extending laterally from the rod projection, a second handle part surrounding the rod projection and having an opening receiving said vane whereby to be held against rotation upon the rod projection and means connected to the upper end of the rod projection to prevent the axial displacement of the second handle part, and said means for retaining the second handle part in place on the rod projection comprising a bolt and said upper end of said rod projection having a threaded opening receiving said bolt.

GUNNAR MADSEN.
